BID SCORING DEVICE FOR CONTRACT AND
AUCTION BRIDGE

Wayne B. Hill, Redondo Beach, Wash.

Application November 15, 1937, Serial No. 174,508

5 Claims. Cl. 273—148)

This invention relates to a bid scoring device which is particularly adapted for use in connection with playing contract or auction bridge, so that a game may be played which may be termed "quiet bridge".

Heretofore in the playing of bridge audible signals were used by each player in indicating their respective bids. Many players commonly in indicating verbally their respective bids would indicate with or without emphasis the character of the bid. In other words, at times players would by their tone of voice indicate a weak, ordinary or strong pass and likewise similar weak, ordinary or strong suit bids or assists.

The rules of the game as generally understood do not contemplate such bidding and by many the practice is considered nothing more or less than cheating.

When a game becomes popular, many people participate therein, not from an interest in the game, but from the desire of association. In other words, many people "sit in" and "hold up" a hand at bridge merely to do what is generally considered as the "thing to do". With such people participating, oftentimes disconcerting conversations occur. In fact, at most bridge parties the game is often interrupted and the attention of the players distracted by general conversation, which is often merely gossip.

It is an object of this invention to provide a novel bid scoring device which will be simple, but which at the same time will be sufficiently interesting so as to permit elimination of undesirable, irritating, and disconcerting talking while the hands are being played.

It is an object of the invention to provide a device which may be used by the players and which will at all times visibly indicate the condition of the bidding so as to eliminate any legitimate reason for conversation.

It is a further object to provide a bid scoring device which will be readily understood and easily used, but which will at the same time be interesting, colorful and fully informative as to the condition of the bidding.

It is a further object to provide means which will permit playing of a card game which may be termed "quiet bridge".

The above mentioned general objects of this invention, together with others inherent in the same, are attained by the device illustrated in the following drawings, the same being preferred exemplary forms of embodiment of this invention, throughout which drawings like reference numerals indicate like parts.

Figure 1 is a plan view of a bid scoring device embodying this invention;

Fig. 2 is a vertical section on a larger scale than Fig. 1, on broken line 2—2 of Figure 1;

Figs. 3 to 9, inclusive, are plan views of markers embodying this invention;

Fig. 10 is a view of the bottom side of Fig. 9;

Figs. 11 to 14, inclusive, are plan views of markers embodying this invention;

Fig. 15 is a view of the bottom side of Fig. 14; 10

Fig. 16 is a fragmentary perspective view on a larger scale than Fig. 1, with the scoring pad partially broken away, showing means for detachably connecting the same to the board; and

Fig. 17 is a vertical section on broken line 15

17—17 of Fig. 6.

A board 20 is formed of any suitable and somewhat rigid material, such as a cardboard. Preferably the board 20 is of a size to fit upon a usual card table. The board may be divided at the 20 middle and a hinge 21 provided for obvious reasons.

Preferably in front of each player, indicated by the conventional symbols N, E, S and W, a bidding zone is provided comprising a plurality 25 of depressions 22 to 32, each provided with indicia thereon, where depression 22 bears "1"; 23 bears "2"; 24 bears "3"; 25 bears "4"; 26 bears "5"; 27 bears "6 little slam"; 28 bears "7 grand slam" and the four depressions 29 to 32 30 each bear "Original bid". The four depressions bearing "Original bid" have been found sufficient for practical purposes to indicate the original bids which a player may make.

Preferably to the side of each player is provided a marker storage zone comprising a plurality of depressions 33 to 44, inclusive, each provided with indicia thereon, where depression 33 bears "Pass"; 34 and 35 bear the symbol of spades; 36 and 37 bear the symbol of hearts; 38 and 39 bear the symbol of diamonds; 40 and 41 bear the symbol of clubs; 42 and 43 bear "No-trump"; and 44 bears "Double and redouble".

Preferably between adjacent players is provided a further marker storage zone comprising depressions 45 to 47, inclusive, each of which has indicia thereon, where depression 45 bears "Stop"; 46 bears "100 honors"; and 47 bears "150 honors".

A "contract zone" comprising depressions 48 to 50, inclusive, is suitably situated such as between two adjacent players. Depression 48 bears "Honors"; 49 bears "1"; 50 bears "2"; 51 bears "3"; 52 bears "4"; 53 bears "5"; 54 bears "6 little slam"; 55 bears "7 grand slam"; and 56 and 57 55

each bear "Double and redouble". This contract zone permits the individual players to clear their respective bidding zones after a contract has been established.

- 5 A scoring pad 58 is suitably attached to the board 20 and may be positioned on the corner of the board 20 diagonally from the "Contract zone". Preferably the board 20 is provided with a slot 59 into which tab 60, carried by score pad 58, is inserted (see Fig. 16). The score pad 58 is provided with a suitable number of pairs of columns, such as three. Each pair comprises two columns with the conventional "We" or "They" above a column.
- 15 Above the columns on the score pad 58 is provided the depressions 61 bearing "Not vul." over each "We" or "They" column. The size of the depressions 61 is such that two markers, such as shown in Figs. 14 and 15, may be inserted 20 therein.

The markers 62 shown in Fig. 3 of the drawings bear the indicia "Pass" thereon and are preferably stored within the depressions 33, which likewise bear the indicia "Pass" thereon. 25 The markers 63 shown in Fig. 4 of the drawings bear the symbol of spades thereon and are preferably stored within the depressions 34 and 35. The markers 64 shown in Fig. 5 of the drawings bear the symbol of hearts thereon and are preferably stored within the depressions 36 and 37. 30 The markers 65 shown in Fig. 6 of the drawings bear the symbol of diamonds thereon and are preferably stored within the depressions 38 and 39. The markers 66 shown in Fig. 7 of the drawings bear the symbol of clubs thereon and are preferably stored within the depressions 40 and 41. 35 Markers 67 shown in Fig. 8 of the drawings bear the indicia "No trump" thereon and are preferably stored within the depressions 42 and 43. The markers 68 shown in Fig. 11 of the drawings bear the indicia "Stop" thereon and are preferably stored within the depressions 45. The markers 69, one face of which is shown in Fig. 9, and the other face in Fig. 10 of the drawings, bear the indicias "Double" and "Redouble" 45 thereon and are preferably stored within the depressions 44. The markers 70 shown in Fig. 12 of the drawings bear the indicia "100 honors" thereon, and are preferably stored within the depressions 46. The markers 71 shown in Fig. 13 of the drawings bear the indicia "150 honors" thereon and are preferably stored within the depressions 47. The markers 72, one face of which is shown in Fig. 14, and the other face in Fig. 15 of the drawings, bear the indicia "Vul." and "Not vul." thereon, and are of a size to be received within the depressions 61.

To minimize the number of markers and the storage depressions to receive the same reversible markers, 69 and 72 have been employed, i. e., "Double" is on one face of markers 69 and "Redouble" is on the other face also "Vul." is found on one face of the markers 72 and "Not vul." is found on the other face. Likewise other 65 reversible markers may be used where desirable.

The various markers 62 to 72, shown in Figs. 3 to 15, inclusive, are shown as square in plan. While such shape is suitable and practical, this invention is not to be limited to any such specific 70 application. Furthermore, the various zones are shown as provided with depressions of a similar shape, which again are to be construed as merely one embodiment of this invention and not a limitation of the same.

75 In using the bid scoring device, the parts of

which have been previously set forth, one mode of operation for contract bridge may be described as follows: First each player is given duplicate markers 63 to 67, inclusive, and single markers 62 and 69. Two adjacent players are provided with single markers 68, 70 and 71. The player adjacent the scoring pad 58, who is keeping score, is provided with duplicate markers 72.

The depressions 33 to 47, inclusive, are provided as a suitable place for the players to segregate their markers and serve as a storage zone. In other words, each player will deposit his marker 62 bearing the indicia "Pass" in depression 33; duplicate markers 63 bearing the symbol of spades in depressions 34 and 35; duplicate markers 64 bearing the symbol of hearts in depressions 36 and 37; duplicate markers 65 bearing the symbol of diamonds in depressions 38 and 39; duplicate markers 66 bearing the symbol of clubs in depressions 40 and 41; duplicate markers 67 bearing "No trump" in the depressions 42 and 43; and marker 69 bearing "Double" and "Redouble" in depression 44. Adjacent players will deposit markers 68, 70 and 71 bearing "Stop", "100 honors" and "150 honors" in the depressions 45 to 47, inclusive.

The score keeper will place the two markers 72 alongside of each other in the depression 61 so the "Not vul." indicia is exposed (when appropriate), indicating that neither side is vulnerable. The score keeper will turn either mark over when either side becomes vulnerable.

At the beginning of the game a penalty for unauthorized talking during the playing of the hand is agreed upon, such as 50 (fifty) points 35 bonus for the offending side.

After the cards are dealt, each player inspects his hand and signifies his bid by placing one of the markers 62 to 67, inc., with which he has been provided, in the bidding zone comprising 40 depressions 22 to 32, inclusive. For example, assuming that "N" is the dealer, if his first bid is one club he will insert one of the club markers 66 in the depression 22 and insert the other club marker 66 in the depression 29, indicating 45 that this one club bid is an original bid. If "N" player desires to pass or to make any bid from 1 to 7 he will place the appropriate marker, of the markers 62 to 67, inclusive, according to the bid, in the appropriate depression 22 to 28, in- 50 clusive, of his bidding zone.

If the bid is other than pass, he will always place the other appropriate marker in the depression 29, indicating that he is making an original bid, and if the same is no trump or the suit thereof. In the event that player "N" desires to pass he places a marker 62 in the depression 22 of his bidding zone.

In the event that the player "E" desires to pass, he places a marker 62 in the depression 22 of his bidding zone. In the event that said player "E" desires to make any bid from 1 to 7, he will place the appropriate marker of the markers 63 to 67, inclusive, according to bid, whether no trump or the suit thereof, in the appropriate depression 22 to 28, inclusive of his bidding zone, always placing the other appropriate marker in the depression 29, indicating that he is making an original bid and whether no trump or the suit thereof. For example, if "E" player desires to bid one diamond, he will place one of his markers 65 in the depression 22 and the other in the depression 29 of his bidding zone, thus indicating that his original bid is a one diamond bid.

In the event that the player "S" desires to 75

raise his partner to two clubs, he will take only one of his markers 66 and place the same in the depression 23 of his bidding zone, indicating that he is raising the bid to 2, but not making an original bid. If, however, player "S" desires to make an original bid, such as one heart, he will take one of his markers 64 and place the same in the depression 22 and the other in the depression 29 of his bidding zone, indicating that he is making an original one heart bid. In the event that the player "S" desires to pass he will place the marker 62 in the depression 22.

In the event the player "W" desires to raise his partner "E" to 2 diamonds, he will place one of his markers 65 in the depression 23 of his bidding zone. If, however, he desires to make an original bid, he will place one of the appropriate markers in the depression 29, indicating that he is making an original bid and the other appropriate marker in one of the depressions 22 to 28, inclusive, indicating the value or number of said bid. If said player "W" desires to pass he will place the marker 62 in the depression 23 of his bidding zone, indicating a pass.

If the player "N" desires to make another original bid, such as spades, he will place one of the markers 63 in the depression 30 and the other marker 63 in the appropriate depression 22 to 28, inclusive, of his bidding zone, indicating the value or number of his spade bid. The players will then continue with their bids, whether they be a pass, an original bid in a new suit, a raise bid in a partner's suit, a double, or a redouble until three successive passes are encountered, which will, according to the rules of contract bridge, close the bidding.

After the contract is established the player obtaining the contract will place one of his markers 62 to 67, inclusive, in the appropriate depression 49 to 55, inclusive, of the contract zone, indicating the value and suit or no trump of the contract established. For example, a heart in the depression 52 will indicate that the contract is four hearts. If the contract has been doubled, the player doubling will remove his marker 69 from a depression 22 to 28 and place the same in one of the depressions 56 or 57 of the contract zone with the indicia reading "Double" visible. If the contract has been redoubled, the player redoubling the same will place his marker 69 in the other depression 56 or 57 with the indicia reading "Redouble" visible. Some players in playing contract bridge claim their honors at the time the contract is established. If this procedure is followed, then the player having the contract will claim his honors by placing either the marker 46 or 47 reading respectively "100 honors" and "150 honors" in the depression 48 reading "Honors" of the contract zone. Some players in playing contract bridge claim their honors after the hand is played and the player claiming his honors will, under such rules, delay claiming the honors until the appropriate time. After the contract is established the hand is played in accordance with the rules of contract bridge, except with the elimination of talking.

It has been found desirable in playing contract bridge with the use of the bid scoring device of this invention to prohibit talking from the time the cards are dealt until after the last play of each hand. Some penalty is provided, such as 50 points premium to the unoffending side for any talking occurring during this silence period. Should it be necessary to interrupt the silence period, so that talking is not prohibited, any

player may remove the marker 68 from its depression 45 and place the same on the table. This will interrupt the silence period and the player may, during this interruption period, call attention to any violation of the rules, such as talking, revoke or any other error. The player calling the interruption period explains his reasons for this action and as soon as the error in question is settled, the marker 68 is returned to the depression 45 and the game proceeds.

After the hand is played, the score keeper writes down the score on the score pad 58 and if the score is sufficient to make either side vulnerable the marker 72 in the depressions 61 is turned over so that at the head of the appropriate side or the column the score will indicate that the side is vulnerable.

By the use of this bid scoring device, it is obvious that at all times during the bidding the condition of the bidding is visibly indicated. In other words, the device will indicate the bid of each party, indicate whether the bid is an original bid, or an assist bid, whether either side is vulnerable, or not vulnerable, and whether any bid has been doubled or redoubled. As soon as the bidding has been completed and the hand is ready to be played, the bidding zone of each party may be cleared and the markers returned to the marker storage depressions, with the exception that the appropriate markers are placed in the contract zone to indicate the value of the contract, and whether the bid has been doubled and possibly redoubled. The value of the contract, as indicated by the contract zone, will be maintained until after the hand has been played. The honors claimed by the parties playing the hand will be indicated before or after the hand is played in accordance with the rules adopted by the particular players involved. With such informative condition of the bidding always visibly indicated to the players, there is no legitimate need for talking while the hand is being played, and the undesirable irritating and disconcerting talking, which was heretofore encountered, may be positively eliminated. Talking may be prohibited during each hand from the time the cards are dealt until the last card is played, or if desired, talking may be completely eliminated from the start of the game until the final card is played for that particular session.

In the event that the parties desire to play auction bridge and use the bid scoring device of this invention, the above rules may be readily adapted to the game, with the following exceptions: The markers 72, indicating vulnerable and not-vulnerable will obviously not be needed. Also the depressions 46 and 47, wherein the markers 70 and 71 are stored, indicating respectively 100 and 150 honors, will have to be changed to provide the proper number of markers and storage depressions to permit scoring the honors. In the event that the talking is allowed between hands, further honor markers will not be needed, as the honors can then be declared to the score keeper.

Obviously, changes may be made in the forms, dimensions and arrangement of the parts of my invention, without departing from the principle thereof, the above setting forth only preferred forms of embodiment.

I claim:

1. In a device of the class described, a board arranged for card playing in the central portion thereof and provided with a bidding zone in each marginal portion thereof adjacent each player, said bidding zone comprising a plurality of de-

- pressions of a size to receive therein markers in the form of relatively thin solids and said depressions bearing indicia indicating bids from one to seven; and a plurality of markers in the form of relatively thin solids and each of which markers is adapted to be placed within one of said depressions of the bidding zone, said markers bearing indicia indicating respectively spades, hearts, diamonds, clubs and no trump. 5
- 10 2. In a device of the class described, a board arranged for card playing in the central portion thereof and provided with a bidding zone in each marginal portion thereof adjacent each player, said bidding zone comprising a plurality of depressions of a size to receive therein markers in the form of relatively thin solids and said depressions bearing indicia indicating bids from one to seven; a plurality of markers in the form of relatively thin solids and each of which markers is adapted to be placed within one of said depressions of the bidding zone, said markers bearing indicia indicating respectively spades, hearts, diamonds, clubs and no trump; and diagonally positioned marker storage zones for joint use by adjacent players comprising a plurality of depressions bearing indicia indicating respectively spades, hearts, diamonds, clubs, no trump, and stop, said depressions being of a size to receive therein said markers for segregation and storage. 15
- 20 3. In a device of the class described, a board arranged for card playing in the central portion thereof and provided with a bidding zone in each marginal portion thereof adjacent each player, said bidding zone comprising a plurality of depressions of a size to receive therein markers in the form of relatively thin solids and said depressions bearing indicia indicating bids from one to seven; and a plurality of markers in the form of relatively thin solids and each of which markers is adapted to be placed within one of said depressions of the bidding zone, said markers bearing indicia indicating respectively spades, hearts, diamonds, clubs and no trump. 20
- 25 4. In a device of the class described, a board arranged for card playing in the central portion thereof and provided with a bidding zone in each marginal portion thereof adjacent each player, said bidding zone comprising a plurality of depressions of a size to receive therein markers in the form of relatively thin solids and said depressions bearing indicia indicating bids from one to seven and indicating a plurality of original bids; and a plurality of markers in the form of relatively thin solids and each of which markers is adapted to be placed within one of said depressions of the bidding zone, said markers bearing indicia indicating respectively spades, hearts, diamonds, clubs and no trump. 25
- 30 5. In a device of the class described, a board arranged for card playing in the central portion thereof and provided with a bidding zone in each marginal portion thereof adjacent each player for indicating all bids and the sequence thereof; and a contract zone for indicating the final contract obtaining in the bidding, said contract zone comprising a plurality of depressions of a size to receive markers in the form of relatively thin solids, said depressions bearing indicia indicating respectively one to seven inclusive, double and redouble. 30
